INHALATOR

Martin A. Jaffe, Yonkers, N.Y., assignor to Sterling Drug Inc., New York, N.Y., a corporation of Delaware

Filed May 5, 1966, Ser. No. 2,177

Term of patent 14 years

(Cl. D83—1)

FIG. 1

FIG. 2

FIG. 4

FIG. 1 is a perspective view of an inhalator showing my new design;

FIG. 2 is a view in side elevation thereof;

FIG. 3 is a plan view thereof, and

FIG. 4 is a perspective view similar to FIG. 1 showing the parts in a different relationship.

I claim:

The ornamental design for an inhalator, as shown.
